UNITED STATES PATENT OFFICE

ARTHUR R. SCHWARZKOPF, OF CHICAGO, ILLINOIS, ASSIGNOR TO THEO. A. KOCHS COMPANY, OF CHICAGO, ILLINOIS, A CORPORATION OF ILLINOIS

BARBER'S POLE

Application filed March 24, 1932. Serial No. 600,905.

This invention relates to a barber's pole of the wall-mounted type. The present improvements have to do with the assembly of the pole parts, and their securement in unitary relation to a base which is attachable to a wall or other structure, the construction being simplified and rendered susceptible of ready disassembly for purposes of repair, replacement, etc.

10 A suggestive embodiment of this invention is set forth in the accompanying drawing, in which—

Figure 1 is a view in vertical section showing the present barber's pole attached to a vertical wall or other supporting structure;

15 Fig. 2 is an enlarged fragmentary section through the upper end of the cylinder and support therefor;

Fig. 3 is a view similar to Fig. 2 showing 20 the lower end of the cylinder and support therefor;

Fig. 4 is an enlarged transverse section on line 4 of Fig. 1; and

25 Fig. 5 is a similar view taken on line 5 of Fig. 1.

In the accompanying drawing is shown a vertical wall W somewhat rough and irregular, as is commonly characteristic of a building front upon which a barber's pole is mounted. Attached to such a wall are a pair 30 of U-shaped clips A, each having outturned feet 6 at its opposite ends through which screws or bolts 5 are passed for anchorage in the wall. Each clip may be further provided 35 with a central opening for receiving a bolt 7 which connects with a pole base B desirably of channel formation. The clips which are attached to the base near its opposite ends 40 serve to mount the latter fixedly upon the wall in slightly spaced relation to the irregular face thereof. This is advantageous because the base may be anchored vertically in place free of interference with such projections as are commonly encountered in a building front made of masonry or the like.

The pole shown comprises a cylinder C supported between upper and lower brackets U and L respectively. In accordance with 50 usual practice, the cylinder is produced desir-

ably of translucent or transparent material with characteristic decoration.

The lower bracket which supports the weight of the cylinder is of hollow construction with a circular wall inwardly flanged at 55 10 to form a seat on which may be rested a flange 11 outturned from a cap 12 whose cylindrical wall depends into the interior of the bracket. An inturned flange 14 at the lower end of the cap forms a support upon 60 which the lower end of the cylinder is rested. The cap which desirably is made of non-corrosive material, such as brass, may be cemented or otherwise secured to the lower end of the cylinder. Its connection with the bracket 65 is such that it may be freely removed therefrom, together with the cylinder, after the bracket is disconnected from the base, as indicated by dotted lines in Fig. 1.

Extending laterally to one side of the 70 bracket is an arm 15 having spaced ears 16 adapted to lie adjacent opposite faces of the base for connection therewith. Such a connection may conveniently be made with screws 17 passing through openings in the 75 two ears for threaded connection with registering openings in the side walls of the base channel. Other ears 18 which extend vertically and oppositely from the arm 15 are adapted to lie upon the front face of the base 80 channel to assist in maintaining the bracket horizontally in position when secured in place as by means of the screws already suggested. To remove the bracket, it is necessary merely that the screws be loosened by 85 use of a suitable instrument applied to the screws from opposite sides of the pole. The bracket is positioned above or below the lowermost clip A, the latter arrangement being 90 suggested in Fig. 1.

Applied over the upper end of the cylinder is the top bracket U also of hollow construction. As shown, this is formed with a depending circular wall 20 terminating in an inturned flange over which may be fitted a 95 gasket 21 of rubber or the like which furnishes lateral support to the proximate end of the cylinder. The upper end of the cylinder may also have applied thereto a reinforcement 22, as of tape or other suitable 100

material. Extending horizontally within the bracket is a spider 23 overlying the top end of the cylinder. To one side of the bracket is a laterally extending arm 25 formed with spaced ears 26 adapted to lie adjacent opposite faces of the base and with other ears 27 extending vertically in opposite directions to lie against the front face of the base.

The upper bracket provides on its upper end a circular wall 30 within which is received the base of a globe 31 secured in place as by set-screws 32. Within the globe is positioned a light 33 supported upon an upwardly extending arm 34 having a mounting 15 in a coupling 35 which is carried by the spider 23. Depending from this coupling is a second arm 36 supporting at its lower end a second light 37 positioned within the cylinder to effect an illumination thereof. The 20 wiring 40 for the lights is extended through the supporting arms therefor, emerging through a lateral opening in the coupling for passage through the arm 25 which is hollow. The arm is connected fixedly to the 25 channel base as by means of a hollow nipple 41 threaded into the end of the bracket arm for extension through an opening into the base to receive at its end a nut 42 bearing against the inside face of the base channel. 30 The wiring continues on through the nipple and through the supporting wall W wherein an insulated bushing 43 may be provided, as shown.

A barber's pole of the kind described will 35 require little, if any, attention when once placed in use. At such time, however, as may be necessary to clean the cylinder or lights, or make repairs, it is necessary merely that the lower bracket be disconnected from the supporting base. When this is done, the cylinder 40 may be slid out from the upper bracket whose position remains undisturbed, this movement being suggested by the dotted lines in Fig. 1. With the cylinder removed, all 45 parts requiring attention are fully exposed so as to facilitate any operations to be performed. The replacement of the cylinder and attachment of the lower supporting bracket is accomplished by the reversal of the 50 movements just described.

This invention is advantageous in its simplicity of the several parts which are assembled in the manner described, and in the complete protection which is afforded to the 55 lights, wiring, etc. The pole may be produced at small cost, and is readily attachable together with its supporting base to a wall of irregular face. Once installed, as herein explained, the base for the pole will remain 60 securely in place, furnishing a mounting which is both convenient and secure for the pole assembly.

I claim:

1. A wall-type barber's pole in which is 65 comprised upper and lower brackets and a

base, the lower bracket being formed to embrace the base on opposite sides and having oppositely extending vertical ears for abutting the base upon the front, means passing laterally into the base for securing the lower 70 bracket removably thereto, a hollow connector for securing the upper bracket to the face of the base, a light carried by the pole, and wiring connections extending from the light through the upper bracket and hollow connector to a source of current. 75

2. A wall-type barber's pole in which is comprised upper and lower brackets and a base, the two brackets being each formed to embrace the base on opposite sides and having oppositely extending vertical ears for abutting the base upon the front, means passing laterally into the base for securing the lower bracket removably thereto, a hollow connector for securing the upper bracket to 80 the face of the base, a light carried by the pole, and wiring connections extending from the light through the upper bracket and hollow connector to a source of current. 85

3. A wall-type barber's pole in which is comprised a cylinder with supporting brackets extended from opposite ends to a base, one bracket being removably connected to the base by means engaging with opposite walls thereof, and the other bracket being secured 90 to the base by a hollow connector traversing the front wall of the base, a light positioned within the cylinder, and wiring connections from the light extended through the connector and base to a source of current, the removable bracket when free of the base permitting disconnection of the cylinder from the other bracket with consequent exposure 95 of the light therewithin. 100

4. A wall-type barber's pole in which is comprised a cylinder supported between two brackets in overlying relation to opposite ends thereof, a base upon which the two brackets are mounted, means removably connecting one bracket to the base, hollow 110 means connecting the other bracket to the base forming a conduit between the interior of the bracket and the far side of the base, a spider within the bracket last named, a coupling carried by the spider, hollow arms oppositely extending from the spider each supporting at its remote end a light, and wiring connections from the two lights extending through the hollow arms and laterally from the coupling through the interior of the proximate bracket and out through the hollow connector to a source of current. 115

5. A wall-type barber's pole in which is comprised a channeled base, a pair of U-shaped clips fitted over the channeled base, each clip having outturned feet adapted when rested against a wall to position the base in spaced relation thereto, means connecting each clip fixedly to the base, and a pair of brackets mounted on the base and supporting 125 130

between them a cylinder forwardly of the base.

6. A wall-type barber's pole in which is comprised a cylinder with upper and lower brackets extended from opposite ends to a base, depending means formed on the lower bracket in engaging relation to the proximate face of the base, screw means in parallelism with the face of the base extending through parts of the lower bracket and the base to connect the one removably to the other, and means securing the upper bracket fixedly to the base.

7. A wall-type barber's pole in which is comprised a cylinder with upper and lower brackets extended from opposite ends to a base, the lower bracket being formed with a seat, and a cap applied to the lower cylinder end receivable within the seat and removable therefrom to disconnect the bracket from the cylinder.
